The ornamental design for a fishers swimmer frog with button shaft skirt holder, as shown.

DESCRIPTION

A portion of the disclosure of the patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a front perspective view of a fishers swimmer frog with button shaft skirt holder showing my new ornamental design.

FIG. 2 is a rear perspective view thereof.

FIG. 3 is a right perspective view thereof.

FIG. 4 is a left perspective view thereof.

FIG. 5 is a top perspective view thereof; and,

FIG. 6 is a bottom perspective view thereof.
